OF MILWAUKEE, WISCONSIN, A CORPORATION OF WISCONSIN

MULTIPLE HYDRAULIC DRIVE

Application filed February 29, 1928. Serial No. 257,935.

This invention relates to multiple hydraulic drive systems for effecting the simultaneous operation of a plurality of independent elements at accurately controlled speeds.

5 For purposes of explanation the invention will be described as embodied in a special type of crank shaft lathe, wherein it is utilized as an accurate feed mechanism for a plurality of independent tools, although it is capable of 10 application to other types of machine tools and to other widely varying arts, such for instances as a multiple pumping system for oil wells.

One object of the present invention is the 15 provision of a hydraulic system through which a plurality of independent elements may be simultaneously driven at accurately regulated rates from a single power source.

Another object is the provision in a multiple drive system of the character mentioned 20 of means for effecting an accurate control of the rate and extent of movement of the several driven elements.

Another object is the provision in a multiple drive system of the character mentioned 25 of means for compensating for leakage losses to thereby maintain proper phase relation between the several driving means.

Another object is the provision in a multiple drive system of the character mentioned 30 of means for temporarily concentrating the entire force of the power source upon any of the several driving means.

Another object is the provision in a multiple drive system of the character mentioned 35 of means for maintaining a different phase relation between the several driving means so that one or more may complete the working stroke ahead of others.

Another object is the provision of improved flexible connections for transmitting driving liquid to each hydraulic driving means.

Other objects and advantages will appear 40 from the following description of an illustrative embodiment of the present invention.

In the drawings:

Figure 1 is a fragmentary plan view of crank shaft lathe equipped with a multiple hydraulic feed system embodying the present 45 invention.

Fig. 2 is a transverse section taken substantially along the line 2—2 of Figure 1.

Figs. 3 and 4 are longitudinal sectional views of two flexibly connected fluid conducting links, which together form a flexible connection for conveying driving liquid to and from each feed cylinder. These sections are taken substantially along the lines 3—3 and 4—4, respectively, of Figure 2.

Fig. 5 is a diagrammatic view of the hydraulic system.

The lathe shown in Figures 1 and 2 is designed to finish in one operation the cheeks *a* of the several cranks *b* of a crank shaft *c* and also the several crank pins *d* thereof. The crank shaft is shown mounted at one end upon a dead center 10 and at the other end in a rotary chuck 11 of a well-known type driven clockwise (Fig. 2) by an appropriate gear 12. The crank shaft is thus rotated about its true axis causing the several pins *d* thereof to follow circular orbital paths concentric with the axis. A plurality of tool supporting frames 13 are mounted to translate within circular orbital paths coextensive with the paths of the several crank pins *d*, respectively, and in phase therewith. In this instance each frame is supported at one end upon an eccentric pin 14 on a shaft 15, driven clockwise (Fig. 2) by a gear 16, and at the other end by an eccentric pin 17, on a shaft 18 driven in the same direction by a gear 19. The three gears 12, 16 and 19 are driven at the same rate through a gear 20 meshing therewith. The axes of the two pins 14 and 17 of each frame are offset equal distances and in the same direction from the axes of their respective shafts 15 and 18, the extent and direction of offset in each instance being equal to the extent and direction of offset of the corresponding pin *d* of the crank shaft *c*, so that each frame moves parallel to itself and in the same phase as the corresponding crank pin *d*.

Each frame carries a tool feeding cylinder 21, 22, 23, or 24 which moves in unison therewith and encloses a piston 25, 26, 27, or 28 closely fitted for lengthwise reciprocation therein. Each frame is also transversely bored to receive and guide a rod 29, 30, 31 or 32 connected with the associated piston and

carrying a lathe tool 33, 34, 35, or 36, adapted to operate upon one of the several pairs of cheeks *a* and crank pins *d*. Each tool is given two distinct motions:—(1) a circular translatory motion, imparted from the translatory motion of its supporting frame, by which it is caused to follow a crank pin *d* in its circular travel about the axis of the crank shaft, and (2) a rectilinear motion toward and from the axis of the crank pin imparted by the movement of its associated piston lengthwise of the cylinders 21, 22, 23 or 24.

The several pistons 25, 26, 27 and 28 are actuated and controlled by a multiple hydraulic drive system such as will now be described. In this system (shown diagrammatically in Figure 5) the rear ends of the several feed cylinders 21, 22, 23, and 24 are hydraulically connected to the forward ends of several impeller cylinders 37, 38, 39 and 40, respectively, through appropriate leads 41, to be hereinafter described; and the forward ends of the several feed cylinders are hydraulically connected to the rear ends of the several impeller cylinders, respectively, through similar leads 42. The several impeller cylinders contain coacting pistons 43, 44, 45 and 46, respectively, which are simultaneously driven by an appropriate cross-head 47 to which they are rigidly connected through appropriate rods 48. The arrangement is such that during each advance stroke of the cross head 47 each of the several pistons 43, 44, 45, and 46 will advance and force liquid at a definite rate through the leads 41 into the several feed cylinders to thereby advance each of the several pistons 25, 26, 27, and 28 at a definite rate, the liquid discharged from the forward end of each feed cylinder returning to the rear end of each impeller cylinder through the respective leads 42; and upon each return stroke of the cross-head the several pistons 25, 26, 27 and 28 are retracted by liquid delivered through the respective leads 42 from the rear ends of the impeller cylinders. The several tools 33, 34, 35 and 36 are thus individually fed at definite rates toward and from the respective crank pins *d* in accordance with the direction and rate of movement of the cross-head 47.

The cross-heads 47 is hydraulically driven in both directions and at controlled speeds by liquid supplied from a reversible flow, variable displacement pump 49 of a well known type. The pump shown is fully described in my copending application Serial No. 199,925, filed June 20, 1927, and it will suffice here to state that it is driven at constant speed from an appropriate source through a shaft 50, the direction and rate of liquid discharged thereby being controlled by a lever 51. With the control lever 51 in the intermediate position shown pump discharge is zero. When shifted toward the right liquid is discharged through outlet 52 at a rate de-

pendent upon the extent of movement of the lever, and liquid returns to the pump through outlet 53; and when the lever is shifted toward the left liquid is discharged through outlet 53 at a rate dependent upon the extent of movement of the lever, and liquid then returns to the pump through outlet 52. In all positions of the control lever the pump maintains a supply of liquid under low pressure with which the outlet 54 communicates. A connection 55 communicates with a liquid reservoir provided in the base 56 of the pump. In this instance the two main circuit outlets 52 and 53 are connected through appropriate hydraulic leads 57 and 58 with the opposite ends of a motor cylinder 59, which coacts with a piston 60 connected with the cross-head 47 through a rod 60'.

Provision is made for automatically controlling the motion of the piston 60 to thereby cause the cross-head 47 to execute a predetermined operating cycle. To this end the pump control lever 51 is placed under the control of an appropriate cam, mounted for movement with the cross-head. Cam shown includes a plate 61 fixed to the cross-head and having an upstanding portion 62 of irregular form shaped to provide a straight edge 63, and a broken inclined edge 64, interrupted by a short straight portion 65. A cam block 66, adjustably fixed to the plate 61 and spaced from the upstanding portion 62, is also of irregular form. One side thereof is shaped to match the portion 62 and the other side is shaped to provide three straight portions 67, 68 and 69 disposed at different distances from the longitudinal center of the block. A pin 70, carried by one arm of a bell-crank 71, is arranged to coact with the faces 63, 64 and 65 of the portion 62 and the faces 67, 68, and 69 of the block to determine the position of the bell-crank during movement of the cross-head. The bell-crank is fulcrumed, as at 72, upon an appropriate fixed bracket 73, and is yieldably urged to swing clockwise by the action of a spring 74. The other end of the bell-crank is connected through a link 75 with an arm 76 projecting from the lever 51, so that the lever is caused to swing upon its fulcrum 77 in accordance with the action of the bell-crank.

With the parts in the position shown the pin 70 is held by the spring 74 in intermediate neutral position against the inclined portion 64 of portion 62, so that the lever 51 is also in neutral position, there is no flow in leads 57 and 58 and the cross-head 47 is at rest. To start the feed motion the lever 51 is manually swung toward the right to thereby shift the bell-crank and pin 70 toward the left and cause the pump to deliver liquid at a high rate through the lead 57 to the rear end of the motor cylinder 59, to thereby advance the piston 60 and cross-head 47. The hand lever 51 is then released and the pin 70

first rides upon the face 67 of the advancing cam block 66 to thereby maintain the advance of the cross-head at a relatively rapid rate. This advance continues until the pin 70 leaves the face 67 and swings toward the right into contact with face 68, thereby swinging the lever 51 a predetermined distance toward neutral position and causing a reduction in pump displacement. The cross-head then continues to advance at a slower rate until the pin 70 leaves face 68 and makes contact with face 69 to effect a similar adjustment of lever 51 and a further reduction in pump displacement. The cross-head then continues to advance at a still slower rate until the pin 70 leaves face 69 and swings into contact with face 63 of portion 62. This action causes the lever 51 to swing through neutral position into an extreme position toward the left, so as to reverse the pump and cause the same to deliver liquid at a high rate through lead 58 into the forward end of the motor cylinder 59, whereupon the cross-head begins a return movement at relatively high speed. This movement continues until the rate is reduced by the action of inclined face 64 upon the pin 70. The straight portion 65 permits the cross-head to travel for a short distance at low speed after which the pin 70 is ultimately returned to the original neutral position by the continued action of face 64 and the cross-head again comes to rest. As hereinabove pointed out the variable speed advance and return movements of the cross-head are transmitted to the several pistons 25, 26, 27, and 28 through the several impeller cylinders 37, 38, 39 and 40 to effect the advance and return of the several tools toward and from their respective crank pins *d*.

Provision is also made for individually limiting the extent of advance and return of each piston 25, 26, 27 and 28 to thereby provide an extremely accurate control for each tool. For this purpose a pair of independently adjustable limiting stops are provided for each tool. In the form shown these stops comprise a pair of set-screws 78 and 79 mounted in suitable lugs 80 and 81 projecting from each tool carrying frame 13. Each pair of screws coacts with an intermediate stop 82 projecting from each of the rods 29, 30, 31, and 32 through a slot 83 in each frame. The engagement of stop 82 against screw 78 limits the advance of the associated tool and the engagement of stop 82 with screw 79 limits the return stroke of the tool.

In the machine shown each of the several hydraulic leads 41 and 42, indicated diagrammatically in Figure 5, consists in part of separate pipe connections through which the opposite ends of the fixed impeller cylinders 37, 38, 39, and 40 communicate respectively with separate passages 41' and 42' leading transversely through a fixed rail 84 attached

in an appropriate manner to the frame of the machine, the leads being completed by pairs of flexibly connected fluid conducting links 85 and 86 through which the several passages 41' and 42' communicate respectively with the opposite ends of the several moving feed cylinders 21, 22, 23 and 24.

Two links of a coacting pair are shown in section in Figures 3 and 4. Each link contains two longitudinal passages 87 and 88 or 87' and 88'. A pintle 89 fixed in and projecting laterally from one end of link 85 is closely fitted to rotate within the adjacent end of link 86 and provides a swivel connection therebetween. Pintle 89 is removably retained in link 86 by appropriate means such as a screw 90 and washer 91. The other end of link 85 is mounted to swing upon a similar pintle 92 fixed in and projecting from a bracket 93 projecting from the rail 84. Pintle 92 is provided with two longitudinal passages 94 and 95 which communicate through ports 96 and 97 and pipes 41" and 42" with the transverse passages in the rail 84, and which also communicate through ports 98 and 99 with the passages 87 and 88 in the link 85. Similarly passages 87 and 88 in link 85 communicate respectively with passages 87' and 88' in link 86 through longitudinal passages 100 and 101 in the pintle 89. A third pintle 102 fixed in the end of link 86 is closely fitted for rotation within the end head 103 of one of the feed cylinders. A longitudinal passage 104 in pintle 102 connects passage 87' in link 86 with a passage 105 leading to the rear end of the feed cylinder and a longitudinal passage 106 connects passage 88' with a pipe 107 leading to the forward end of the feed cylinder. The hydraulic leads for both ends of each feed cylinder are thus provided by a single pair of links connected in such manner as to permit free movement of the cylinder with its supporting frame 13.

Each lead 41 and 42 is connected with a high pressure relief valve 108 of a well known type. In this instance each of the several relief valves is mounted upon the rail 84 in communication with one of the passages 41' or 42' in the rail, the liquid passing each valve being permitted to escape through a pipe 109 into a longitudinal passage 110 in the rail. Passage 110 communicates through an appropriate lead 111 and connection 55 with the liquid reservoir in the base of the pump. A second longitudinal passage 112 in the rail is maintained flooded with liquid under low pressure supplied from the pump through the connection 54 and lead 113. A check valve 114 between the passage 112 and each of the several passages 41' and 42' permits the admission of liquid thereto from passage 112 whenever the pressure in any of the several main leads 41 and 42 falls below that in the passage 112. These leads are thus always

maintained flooded with liquid under pressure. A third longitudinal passage 115 in the rail is permanently connected through a lead 116 with the power lead 57 leading to 5 the rear end of the motor cylinder 59. A check valve 117 between the passage 115 and each of the passages 41' permits liquid to escape from any of the leads 41 whenever the pressure therein exceeds the pressure in the 10 passage 115.

The stroke of the cross-head 47 is such that it continues to advance for a brief time interval after all of the tool feeding pistons 25, 26, 27 and 28 have been arrested by the 15 engagement of their respective stops 82 against the coacting screws 78, and such that it continues its return movement for a brief time interval after all of the feed pistons have been arrested by the engagement of their respective 20 stops 82 against the coacting screws 79. During the continued advance of the several impeller pistons 43, 44, 45 and 46, after the advance of the corresponding feed pistons has been arrested, the excess liquid in 25 the several leads 41 escapes through the corresponding high pressure relief valves 108, and liquid under low pressure is admitted to the several leads 42 through the corresponding check valves 114 to thereby maintain these 30 leads and the rear ends of the impeller cylinders 37, 38, 39 and 40 flooded. The several feed pistons are thus in readiness to start simultaneously on a return movement immediately upon the reversal of movement of 35 the cross-head. In a similar manner excess liquid is permitted to escape from the several leads 42 through their respective high pressure relief valves 108, and liquid is admitted to the several leads 41 through their 40 respective check valves 114 to keep the same flooded, during the continued return movement of the several impeller pistons after the return movement of the several feed pistons has been arrested by the stop screws 79; 45 and the several feed pistons are thus in readiness to advance simultaneously immediately upon the next advance of the cross-head. A hydraulic compensating system is thus provided with functions to maintain a definite 50 operating phase relation between the several feed pistons in spite of any leakage losses in the system.

It will be noted that during both the advance and return strokes of the impeller and 55 feed pistons the several cylinders of each group receive their supply of liquid primarily from the discharge of liquid from the several cylinders of the other group. To make the rate of discharge from each cylinder of one group exactly equal to the intake demand required by a connected cylinder of the other group is a practical impossibility due to unavoidable leakage and mechanical inaccuracies. This leads to serious difficulties. For instance, if during the return stroke 60

of piston 25 the rate of discharge from the rear end of cylinder 21 be only slightly greater than the rate of supply demanded by the cylinder 37, an excessive back pressure is set up in the lead 41 causing the piston 25 to 70 stop, or, similarly, if during the advance movement of piston 25, the rate of discharge from the forward end of cylinder 21 is only slightly greater than the rate of supply demanded by cylinder 37, an excessive back 75 pressure is immediately set up in lead 42. To remedy this condition the several impelling and feed cylinders, and their cooperating rods 48 and 29, 30, 31 and 32, are so proportioned that during the advance stroke the 80 rate of discharge from the forward end of each feed cylinder is slightly less than the supply demand of the rear end of the associated impeller cylinder, liquid being admitted to each of the leads 42 through the 85 check valves 114 to make up for this deficiency and thereby keep the impeller cylinders full. During this advance the several check valves 117, hereinabove mentioned, are kept closed by the pressure in passage 115 transmitted 90 from the working pressure in the lead 57 by which the piston 60 is advanced. With the cylinders and rods thus proportioned the rate of discharge from the rear end of each feed cylinder, during the return stroke, is slightly 95 in excess of the supply demand of the forward end of the associated impeller cylinder. During the return stroke however the pressure in the lead 57 is of course reduced, since this lead is then only carrying the discharge from cylinder 59, and the several 100 check valves 117 function to permit the escape of excess liquid from the several leads 41 and thus prevent the building up of excessive pressures therein. The check valves 117 together with check valves 114 thus effectively 105 compensate for inequalities between rates of discharge and supply demands of the connected cylinders.

A brief description of the operation of the 110 machine will now be given. Let it be assumed that the crank shaft *c* has been applied, as indicated, and that the three gears 12, 16, and 19 are rotating clockwise (Fig. 2) under the 115 action of the driving gear 20, so that the crank shaft is rotating clockwise, the several crank pins *d* are following a circular path, and the several tool carrying frames 13 are translating with a circular motion similar to and in exact phase with the respective 120 crank pins. Let it also be assumed that the several feeding pistons 25, 26, 27, and 28 are retracted so that the several tools 33, 34, 35 and 36 are withdrawn from the work, and that the cross-head 47, cam block 66, pin 70, and control lever 51 are in the respective positions indicated in Figure 5. To start an operating cycle the operator shifts the hand lever 51 into right extreme position, whereupon the pump delivers liquid at a high rate 125

through the lead 57 and the cross-head 47 and impelling pistons 43, 44, 45 and 46 advance rapidly. The operator then releases the lever 51 and permits the pin 70 to ride upon the face 67 of the cam block and the rapid advance continues. During this advance the several feed pistons 25, 26, 27 and 28 are advanced at a corresponding rate causing the several tools to advance toward the work. Just before the tools are actually engaged between the several pairs of cheeks *a* on the crank shaft the pin 70 leaves face 67 and contacts with face 68 of the cam block to thereby reduce the rate of advance of the cross-head 47 in the manner hereinabove described, whereupon the rate of advance of the several tools is correspondingly reduced to a rate appropriate for a light cutting feed. This rate of advance continues until just prior to actual engagement of the cutters with the several crank pins, at which time the pin leaves the face 68 and contacts with face 69 to thereby further reduce the rate of advance to that appropriate for a heavier cutting feed. This slow advance of the tools continues until each is arrested by contact of its associated stop 82 against the cooperating screw 78. Thereafter the slow advance of the cross-head 47 continues until the pin 70 leaves the face 69 of cam block 66 and shifts into contact with face 63 of portion 62, whereupon the pump reverses and the cross-head begins a rapid return stroke as hereinabove described. As the cross-head reverses its motion the several feed pistons 25, 26, 27 and 28 are simultaneously actuated and begin a rapid return movement withdrawing the several tools from the work. This movement of the tools continues until the speed is reduced by contact of the pin 70 with the face 64 of portion 62, and about the time the pin reaches the straight portion 65 of portion 62 the several stops 82 engage the screws 79 and the several feed pistons and tools come to rest. Thereafter the cross-head 47 continues its return movement, but at a gradually reduced rate until the pin 70 is returned to neutral position by the action of face 64 and the cross-head comes to rest.

It will be noted that the cut becomes considerably heavier as the tools, near the end of their forward feeding stroke, engage their respective crank pins, and in order to avoid an excessive peak load on the machine from this cause, provision is preferably made by which the several tools may be advanced into contact with their respective crank pins successively rather than simultaneously. This is accomplished by so adjusting the several screws 79 as to stop the several feed cylinders and tools at different points in their return strokes. For example, as indicated in Figure 5, the feed piston 25 has been permitted to return a greater distance than the feed pis-

ton 26, by reason of a variation in the setting of their respective stop screws 79, and tool 34 (connected with piston 26) is correspondingly advanced with respect to tool 33 (connected with piston 25). Both tools 33 and 34 move forwardly simultaneously and at the same rate during the next advance stroke of the cross-head 47, with the result that tool 34, in advance of tool 33, actually engages its crank pin and completes the cut thereon before tool 33 reaches its crank pin.

Provision is also preferably made for concentrating the entire force of the power source upon any one of the several tools to thereby render available a pulling force of sufficient magnitude to extract a tool from the work in the event of a jam. To this end provision is made for rendering any of the several high pressure relief valves 108 ineffective and for adjusting and retaining any of the check valves 114 in open position. In this instance a valve in the form of a stem 118, is screwed into the rail 84 beneath each relief valve 108, and is provided with a tapered end 119 adapted to enter and close the inlet port 120 of the relief valve, to thereby render the same ineffective; and a stem 121 is screwed into the rail 84 beneath each check valve 114 where it may be adjusted into contact therewith to lift and retain that valve in open position. Should the tool 33, for instance, become jammed in the work the relief valve 108, connected with the lead 42 from impeller cylinder 37, is rendered ineffective by adjustment of the stem 118 in the manner just described, and the three check valves 114, connected with the leads 42 from the other three impeller cylinders, are opened by adjustment of their respective stems 121 in the manner just described so these three leads are all open to the low pressure passage 112. With the valves thus adjusted the cross-head 47 is made to execute a return stroke, and since the three impeller pistons 44, 45, and 46 offer no appreciable resistance to this movement of the cross-head practically the entire force of the motor cylinder 59 is concentrated upon the impeller piston 43, to thereby force liquid through the lead 42 to cylinder 21 at high pressure. Since the relief valve 108 connected with this lead has been rendered ineffective, the pressure therein is limited only by the force transmitted from the motor cylinder through piston 43. This is ordinarily sufficient to extract the tool.

Various changes may be made in the embodiment of the invention hereinabove specifically described without departing from or sacrificing the invention as defined in the appended claims.

I claim:—

1. In a multiple hydraulic drive system the combination of a plurality of liquid impelling means, means for simultaneously driving the

same at regulated rates, a plurality of separate hydraulically actuated means, a plurality of separate hydraulic connections between said plurality of impelling means and said plurality of actuated means, respectively, through which said actuated means are individually driven at regulated rates, and hydraulic compensating means automatically operable to maintain a definite operating phase relation between said plurality of actuated means.

2. In a multiple hydraulic drive system the combination of a plurality of reciprocating liquid impelling means, means for simultaneously reciprocating the same at regulated rates, a plurality of separate hydraulically actuated reciprocating means, separate hydraulic connections between said plurality of impelling means and said plurality of actuated means through which said actuated means are individually reciprocated at regulated rates, and hydraulic compensating means automatically operable to maintain a definite operating phase relation between said plurality of actuated means.

3. In a multiple hydraulic drive system the combination of a plurality of impeller cylinders and coacting pistons, means for effecting relative reciprocation between said pistons and cylinders simultaneously and at regulated rates, a second plurality of cylinders and coacting pistons, individual hydraulic connections between said first and second named cylinders, respectively, for effecting relative reciprocation between said second plurality of cylinders and coacting pistons at regulated rates, and hydraulic compensating means automatically operable to maintain a definite operating phase relation between said second plurality of cylinders and coacting pistons.

4. In a multiple hydraulic drive system the combination of a plurality of reciprocating liquid impelling means, means for simultaneously reciprocating the same, a plurality of separate hydraulically actuated reciprocating means, separate hydraulic connections between said plurality of impelling means and said plurality of actuated means, respectively, through which the latter are individually reciprocated, and means for arresting the motion of said actuated means prior to the completion of each stroke of said connected impelling means, respectively.

5. In a multiple hydraulic drive system the combination of a plurality of liquid impelling means, means for simultaneously driving the same, a plurality of separate hydraulically actuated means, separate hydraulic connections through which each of said last named means is individually driven by one of said plurality of impelling means, and an adjustable stop for limiting the extent of movement of each of said actuated means.

6. In a multiple hydraulic drive system the combination of a plurality of liquid impelling means, means for simultaneously driving the same, means for controlling the extent of movement of said impelling means collectively, a plurality of hydraulically actuated means each driven by one of said plurality of impelling means, and means for controlling the extent of movement of said plurality of actuated means individually.

7. In a multiple hydraulic drive system the combination of a plurality of liquid impelling means, means for simultaneously driving the same, a plurality of hydraulically actuated means, separate hydraulic connections through which said last named means are individually driven by said plurality of impelling means, respectively, means for reversing the direction of motion of said impelling means to thereby reverse the motion of said actuated means, and adjustable stops for limiting the extent of movement of said actuated means in both directions of motion.

8. In a multiple hydraulic drive system the combination of a plurality of liquid impelling means, means for simultaneously driving the same at regulated rates, means for regulating the rate and extent of movement of said impelling means, a plurality of hydraulically actuated means each driven by one of said plurality of impelling means at rates corresponding to the rate of movement of said impelling means, and adjustable stops for individually limiting the extent of movement of said actuated means.

9. In a multiple hydraulic drive system the combination of a plurality of liquid impelling means, means for simultaneously driving the same at regulated rates, means for automatically regulating the rate of movement of said impelling means, and a plurality of hydraulically actuated means each driven by one of said plurality of impelling means at rates corresponding to the rate of motion of said impelling means.

10. In a multiple hydraulic drive system the combination of a plurality of liquid impelling means, means for driving the same at regulated rates, means responsive to the movement of said driving means for automatically varying the rate of movement of said impelling means, and a plurality of hydraulically actuated means each driven by one of said plurality of impelling means at rates corresponding to the rate of movement of said impelling means.

11. In a multiple hydraulic drive system the combination of a plurality of liquid impelling means, hydraulic driving means therefor including a variable displacement pump, means for varying pump displacement to vary the rate of movement of said impelling means, and a plurality of hydraulically actuated means each driven by one of said plurality of impelling means at rates

corresponding to the rate of movement of said impelling means.

12. In a multiple hydraulic system the combination of a plurality of liquid impelling means, hydraulic driving means therefor including a variable displacement pump, means responsive to the action of said driving means for regulating pump displacement, a plurality of hydraulically actuated means each driven by one of said impelling means, and means for individually controlling the extent of movement of said plurality of actuated means.

13. In a multiple hydraulic system the combination of a plurality of liquid impelling means, hydraulic driving means therefor including a variable displacement pump, means for regulating pump displacement to regulate the rate of movement of said impelling means, a plurality of hydraulically actuated means each individually driven by one of said impelling means, and means for controlling the extent of movement of each of said actuated means.

14. In a multiple hydraulic system the combination of a plurality of liquid impelling means, hydraulic driving means therefor including a variable displacement pump, a plurality of hydraulically actuated means, an individual hydraulic connection between each of said impelling means and one of said actuated means through which the latter are driven, positive stops for arresting the movement of said actuated means, and liquid escape means within said connections permitting continued action of said impelling means after said actuated means have stopped.

15. In a multiple hydraulic system the combination of a plurality of liquid impelling means, means for driving the same in either direction, a plurality of hydraulically actuated means, a separate reversible flow hydraulic circuit between each of said impelling means and one of said actuated means through which the latter are driven, means including a check valve associated with one side of each of said circuits for supplying liquid under low pressure thereto, means including a check valve associated with the other side of each of said circuits for permitting the escape of liquid therefrom, and means for maintaining said last named check valves closed during operation of said actuated means in one direction.

16. In a multiple hydraulic drive system the combination of a plurality of liquid impelling means, means for driving the same simultaneously in one direction, a plurality of hydraulically actuated means each individually driven by one of said impelling means, and means adjustable to direct the entire energy of said driving means to any of said actuated means to the exclusion of the others.

17. In a hydraulic drive the combination

of a liquid impeller, hydraulically actuated means, and a flexible liquid conducting connection between said impeller and means through which the latter is driven, said connection comprising a pair of links each having a pair of separate liquid conducting passages therein, a pintle forming a pivotal connection between said links and having a pair of separate passages therein, side ports in said pintle each communicating with one of said pintle passages and with one of said passages in one of said links, and additional side ports in said pintle each communicating with one of said pintle passages and with one of said passages in the other of said links.

18. In a machine tool or the like the combination of a rotary work holder, a tool support operating to cause the tool to follow the work during rotation of said holder, and a hydraulically actuated feed mechanism for the tool for advancing the tool into the work during movement of said holder and support.

19. In a machine tool or the like the combination of a rotary work holder, a plurality of separate tool supports operable to cause the supported tools to follow different portions of the work during rotation of said holder, and hydraulically actuated feed mechanisms for simultaneously advancing the tools into the work during movement of said holder and work supports.

20. In a machine tool or the like the combination of a rotary work holder, a plurality of separate tool supports operable to cause its supported tools to follow different parts of the work during rotation of said holder, a hydraulically actuated feed mechanism for each tool movable with its support, and means including a variable delivery pump for effecting the simultaneous operation of said feed mechanisms at predetermined rates.

21. In a machine tool or the like the combination of a plurality of separate feed mechanisms, hydraulically actuated means for driving each feed mechanism, a variable displacement pump, and a hydraulic power transmission system between said pump and means for effecting the simultaneous operation of said feed mechanisms at rates corresponding to pump displacement.

22. In a multiple hydraulic drive the combination of a plurality of separate hydraulically actuated means, a variable displacement pump, and a hydraulic power transmission system between said pump and means for effecting the simultaneous operation of said means at rates corresponding to pump displacement.

23. In a multiple hydraulic drive the combination of a plurality of separate hydraulically actuated means, a variable displacement pump, a hydraulic power transmission system between said pump and means for simultaneously driving said separate means at rates corresponding to pump displacement,

and means for automatically varying pump displacement to thereby simultaneously modify the action of said separate means.

24. In a machine tool, a series of tool holders and means for feeding the same, comprising a series of operating members, a series of cylinders, and pistons in the cylinders coupled to drive the said operating members, a series of pump elements arranged to supply fluid to the series of cylinders so as to move the pistons therein, a common element operatively related to all of the pumps to operate the same, and means for driving the common element.
- 15 25. In a machine tool, a series of tool holders and means for feeding the same, comprising a series of operating members, a series of cylinders, and pistons in the cylinders coupled to drive the said operating members, a series of pump elements arranged to supply fluid to the series of cylinders so as to move the pistons therein, a common element coupled mechanically to all of the pumps to operate the same, and means for driving the common element.

26. In a machine tool, a series of tool holders and means for feeding the same, comprising a series of operating members, a series of cylinders having pistons therein, said pistons being coupled to the operating members, a second series of cylinders having pistons therein, a common operating member for said last named pistons, and connections from the cylinders of the second series to the cylinders 35 of the first series so arranged that a fluid set in motion by the pistons of the second series enters the cylinders of the first series and operates the same.

27. In a machine tool, a series of tool holders and means for feeding the same, comprising a series of operating members, a series of cylinders, and pistons in the cylinders coupled to drive the said operating members, a series of pump elements arranged to supply fluid to the series of cylinders so as to move the pistons therein, a common element coupled mechanically to all of the pumps to operate the same, and means for driving the common element, said means comprising a cylinder and a piston therein connected to the common element, and means for supplying fluid under pressure to operate the piston last named.

28. In a machine tool, a series of tool holders and means for feeding the same, comprising a series of operating members, a series of cylinders, and pistons in the cylinders coupled to drive the said operating members, a series of pump elements arranged to supply fluid to the series of cylinders so as to move the pistons therein, a common element coupled mechanically to all of the pumps to operate the same, and means for driving the common element, said means comprising a cylinder and a piston therein connected to

the common element, and means for supplying fluid under pressure to operate the piston last named, said means being of a type to deliver a constant flow of fluid at varying opposing pressures.

29. In a machine tool, a series of tool holders and means for feeding the same, comprising a series of operating members, a series of cylinders, and pistons in the cylinders coupled to drive the said operating members, a series of pump elements arranged to supply fluid to the series of cylinders so as to move the pistons therein, a common element coupled mechanically to all of the pumps to operate the same, and means for driving the common element, said means comprising a cylinder and a piston therein connected to the common element, and means for supplying fluid under pressure to operate the piston last named, said means being of a type to deliver a constant flow of fluid at varying opposing pressures, said tool holders, operating members, cylinders and pistons being arranged as a series of tool operating systems, said systems as a whole movably mounted with relation to said pumps, and flexible conduits connecting the pumps to said cylinders.

30. In a machine tool, a series of tool holders and means for feeding the same, comprising a series of operating members, a series of cylinders, and pistons in the cylinders coupled to drive the said operating members, a series of pump elements arranged to supply fluid to the series of cylinders so as to move the pistons therein, a common element coupled mechanically to all of the pumps to operate the same, and means for driving the common element, a control means for the said machine tool, and connections from said common member to operate said control means automatically.

31. In a machine tool, a series of tool holders and means for feeding the same, comprising a series of operating members, a series of cylinders, and pistons in the cylinders coupled to drive the said operating members, a series of pump elements arranged to supply fluid to the series of cylinders so as to move the pistons therein, a common element operatively related to all of the pumps to operate the same, and means for driving the common element, each of said tool holders having positive stops.

32. In a machine tool, a series of tool holders and means for feeding the same, comprising a series of operating members, a series of cylinders, and pistons in the cylinders coupled to drive the said operating members, a series of pump elements arranged to supply fluid to the series of cylinders so as to move the pistons therein, a common element coupled mechanically to all of the pumps to operate the same, and means for driving the common element, a control means for the said machine tool, and connections from said com-

mon member to operate said control means automatically, each of said tool holders having positive stops.

33. An hydraulically operated system for the operation of a series of working members of a machine tool comprising a source of hydraulic pressure of a type to deliver a constant flow of liquid at varying pressures, a master cylinder to which liquid is delivered from said source, and a series of separate hydraulic power delivery systems, one for each working member, each of said separate systems deriving its energy from said master cylinder.

34. An hydraulically operated system for the operation of a series of working members of a machine tool comprising a source of hydraulic pressure of a type to deliver a constant flow of liquid at varying pressures, a master cylinder to which liquid is delivered from said source, and a series of separate hydraulic power delivery systems, one for each working member, each of said separate systems deriving its energy from said master cylinder, said power delivery systems each comprising a hydraulic cylinder and piston for each working member and movable therewith, and flexible conduit means whereby hydraulic pressure is delivered to each of said cylinders.

In witness whereof, I hereunto subscribe my name this 11th day of February, 1928.

JOHN P. FERRIS.
